UNITED STATES PATENT OFFICE

172,271

TRAY

Urban H. Despres, Clinton, Maine, assignor to Keyes Fibre Company, Portland, Maine, a corporation of Maine

Application September 30, 1952, Serial No. 21,659

Term of patent 14 years

(Cl. D44—10)

To all whom it may concern:

Be it known that I, Urban H. Despres, a citizen of the United States of America, residing at Clinton, county of Kennebec, State of Maine, have invented a new, original, and ornamental Design for a Tray, of which the following is a specification, reference being had to the accompanying drawing forming part thereof.

Fig. 1 is a top plan view of a tray, showing my new design; and,

Fig. 2 is a side elevational view of the tray of Fig. 1.

What is claimed:

The ornamental design for a tray, as shown.
